UNITED STATES PATENT OFFICE.

JOHN H. MELAVIN, OF CAMBRIDGE, MASSACHUSETTS, ASSIGNOR OF ONE-HALF TO JOSEPH E. DOHERTY, OF BOSTON, MASSACHUSETTS.

HOSE-NOZZLE

SPECIFICATION forming part of Letters Patent No. 669,845, dated March 12, 1901.

Application filed August 23, 1900. Serial No. 27,795. (No model.)

To all whom it may concern:

Be it known that I, JOHN H. MELAVIN, of Cambridge, in the county of Middlesex and State of Massachusetts, have invented certain new and useful Improvements in Hose-Nozzles, of which the following is a specification.

This invention relates to nozzles for regulating the flow of water from a hose, and is particularly adapted for use in washing carriages or woodwork, where rapid changes in the velocity and shape of the jet are required.

The invention consists in the improvements which I will now proceed to describe and claim.

Of the accompanying drawings, forming a part of this specification, Figure 1 represents a longitudinal section of a nozzle embodying my invention. Fig. 2 represents a perspective view showing the method of operating the nozzle by one hand.

The same reference characters indicate the same parts in both the figures.

Referring to the drawings, the nozzle comprises a rigid metallic section *a*, having at one end an internally-threaded portion *l*, into which is screwed the threaded coupling of a hose *e*, and at its other end a threaded portion *m*, to which is attached the flexible delivery-section *k*, which has a body portion of rubber or other elastic material and an internally-threaded metallic bushing *k'*, detachably engaging the externally-threaded portion *m*. The rigid section *a* is divided into two parts by a partition *b*, through which the water may flow by way of an opening *c*, which is surrounded by a valve-seat and is normally closed by a valve *d*, that is held against its seat by the pressure of the water in the hose and by a spiral spring *f*. The thrust of the spring *f* is sustained by a plug *j*, which is screwed into the section *a* and may be removed to allow the removal of the spring *f* and valve *d*. To allow the flow of water through the nozzle, the valve *d* is forced away from its seat by pressure of the hand of the operator against the button or push-knob *h*, which acts on the valve through a stem *g*, which passes into the section *a* through a stuffing-box *p* and is attached at its opposite ends to the knob and the valve.

The outer surfaces of the knob *h* and the section *a* are preferably covered with rubber to guard against scarring of the articles operated on through carelessness of the operator.

In using this device the nozzle is held in such a way that the knob may be pressed inward by the ball of the thumb, while the flexible tip of the nozzle is held between the thumb and forefinger of the same hand, as shown by Fig. 2. By pinching the end of the portion *k* the outlet may be contracted, thus increasing the velocity of the jet and altering its shape and character. At the same time the pressure on the knob may be varied to alter the pressure of water flowing to and through the flexible delivering-section, this change being effected by a portion of the same hand the fingers of which are employed for varying the size or shape of the outlet. Therefore the user may employ one hand for another purpose, such as turning a wheel of the carriage being washed, and with the other hand not only cause the water to flow full force or stop or vary between these points, but also change the character or shape of the jet, whether the latter is slight or on full force. When the nozzle is released, the valve automatically closes and stops the flow of water. Ordinarily for washing carriages and the like a flexible hose without a nozzle is used, the variations in shape and velocity of the jet being caused, as in this case, by pinching the end of the hose; but when, as often happens, the end of the hose is dropped the water continues to flow uselessly and considerable waste results, which is prevented by the use of a device such as the one described. On the other hand, however, none of the nozzles now in use having means for shutting off the water are suitable for the purpose indicated, as the water issues from them in their different adjustments with either too much or too little force and the jet is too compact or too finely divided as spray. In addition the changes in the character of the jet cannot be made with sufficient ease or rapidity.

I claim—

1. A nozzle having two liquid-controlling means, one for varying the pressure of water on its way to the outlet of the nozzle and the

other for varying the shape or character of the jet, the said two controlling means being adapted to be independently operated by different portions of one hand of the user.

5. 2. A nozzle comprising a rigid section having a valve-seat, a spring-controlled valve yieldingly held against said seat and normally closing the waterway through the rigid section, said valve having a stem projecting 10 through one side of the rigid section and provided at its outer end with a push-knob, and a flexible section detachably secured to the rigid section and having a compressible de-

livering end, the relative positions of the push-knob and the compressible delivering end being such that the push-knob may be pressed inwardly by the ball of the thumb and the delivering end compressed by the thumb and forefinger of the hand holding the nozzle, substantially as described. 15

In testimony whereof I have affixed my signature in presence of two witnesses.

JOHN H. MELAVIN. 22
